(57) **CLAIM**

The ornamental design for a user interface for a portion of a display screen, as shown and described.

DESCRIPTION

The FIGURE is a front view of a user interface for a portion of a display screen showing our new design. The broken line drawings of a portion of a display screen, the interior rectangle, the upper right and lower right rectangles, and the small elements on the bottom edge are for illustrative purposes only and form no part of the claimed design.

UNITED STATES PATENT AND TRADEMARK OFFICE
CERTIFICATE OF CORRECTION

PATENT NO. : Des. 543,552 S
APPLICATION NO. : 29/237243
DATED : May 29, 2007
INVENTOR(S) : Hally et al.

Page 1 of 3

It is certified that error appears in the above-identified patent and that said Letters Patent is hereby corrected as shown below:

The title page showing the illustrative printed figure should be deleted to be replaced with the attached title page.

The drawing sheet consisting of fig. 1, should be deleted to be replaced with the drawing sheet consisting of fig. 1, as shown on the attached page.

Signed and Sealed this

Nineteenth Day of October, 2010

David J. Kappos
Director of the United States Patent and Trademark Office
